HINGE FOR WINDOWS, DOORS, GATES
AND THE LIKE

Wolfgang Friedrich Ramien, Cardinal Heights, Ontario, Canada, assignor to Prasmeta Präzisionsmetall- und Kunststofferzeugnisse G. Baumann & Co., Köln-Hohenberg, Germany

Filed Dec. 10, 1958, Ser. No. 779,433

Claims priority, application Germany Mar. 19, 1958
6 Claims. (Cl. 16—159)

This invention relates to a hinge for windows, cabinet doors, rooms, and for gates and the like.

Hinges for the purposes mentioned above which, instead of the usual leaves to be sunk into the wood or the like and to be screwed thereon, are provided with pins to be sunk into the wooden parts are known. Each part of these known hinges, i.e., the upper and lower part, is provided with the pin. One of the hinge parts, generally the lower part, is provided with a pintle which extends in the longitudinal axis of the hinge part and on which the upper hinge part can be slipped by means of an appropriate recess. In order to prevent the pintle of the lower hinge part from turning about the axis of the pin which is sunk into the wood, the position of the lower part of the known hinges is locked by means of a locking pin which is driven through the perforated pin sunk into the wood. Since the position of the perforation in the pin of the fastened lower part is not recognizable from the outside, a special gage is required for this purpose. However, in spite of using this gage, it is not warranted that the locking pin is driven in satisfactorily so that damage to the wood may occur. Moreover, replacement of a hinge part is only possible with difficulty in case of the known method of locking the hinge part in adjusted position.

An object of this invention is to provide simplification and improvement of the method of preventing the hinge parts from being turned out of position, and of the construction of the hinges themselves. The invention is characterized in that turning out of position is prevented by means of a locking member which acts directly on the pintle of the hinge part or its cylindrical member, preferably of the lower hinge part. The locking member and the associated pin are arranged at as great a distance as is possible thereby achieving most effective locking of the hinge part in adjusted position.

It is a further object of the invention to construct the cylindrical member and the pin as one integral part. For this purpose, the pin is combined with the cylindrical member consisting of a casting to form one single part. The cylindrical member or barrel is preferably made of a die-cast metal or of an injection-molded plastic material. That part of the pin which is imbedded in the casting may be roughened, e.g. knurled, at the end which engages the casting. However, the pintle and the pin may form one single piece. Since these members are positioned at a right angle with respect to each other, the member to be imbedded would be of angular shape and, therefore, be held firmly in the casting without the possibility of being turned out of position and pulled out.

The advantage of manufacturing the hinge part in a manner that at least the pintle and the pin form one single piece held together by the casting resides in the fact that substantial simplification of manufacture is achieved and that even in case of very small thickness of the casting jacket as compared with the mass of the inserted part, the latter has a surprisingly snug fit and is firmly held without the possibility of being dislocated. The threads are preferably formed on the pins by rolling-on after insertion into the casting.

Finally, it is an object of this invention to provide hinges where the distance between the pins of the hinge parts is

2

always the same irrespective of the size of hinges. Due to this fact, only a single striking tool is required for different sizes of hinges, i.e. lengths of hinge barrels. This simplifies warehousing of the costly mounting tools (often also referred to as gages).

The object of the invention is illustrated on the appended drawings showing several embodiments and where

FIG. 1 is an exploded plan view of the hinge of the invention;

10 FIG. 2 shows a staple used as the locking member;

FIG. 3 shows an eye screw used as the locking member;

15 FIG. 4 shows the hinge joint of the invention as mounted on a rabbeted door;

FIG. 5 is an exploded sectional view showing a further

embodiment of the lower part of the hinge;

15 FIGS. 6, 7, and 8 show further forms of the pin;

FIG. 9 illustrates a further detail of the hinge of the invention using different sized pins;

20 FIG. 10 is a cross sectional view illustrating a further embodiment of the hinge of the invention, and FIG. 11 is a sectional view taken on line XI—XI of FIG. 10.

The hinge comprises barrel portions 1 and 2 provided with laterally extending pins 3 and 5, respectively, which are driven or screwed into the stationary frame and 25 the door leaf or the wing of a window, etc., respectively. The hinge part 1 as the lower part is provided with the pintle 4. The upper part 2 is provided with a bore 6 to receive the pintle 4 so that the hinge parts may be pivotally connected. In special cases, the pintle 4 may also be 30 provided at the upper hinge part while the lower part has the associated bore. To prevent the hinge part bearing the pintle 4, e.g. the lower part 1, from being turned out of its adjusted position, a locking member 7 is provided which, for example, may engage a bore 8 provided in the 35 hinge part 1. The locking member 7 may be threaded at its end to be driven into the frame while the other end may be provided with a screw slot 9.

As shown in FIG. 2, the locking member may also be in the form of a staple 12 which is driven into the wood over 40 the pintle 4 after the hinge part bearing the pintle 4 has been screwed in or driven in and which, at the pintle 4, has the form of a washer.

As shown in FIG. 3, an eye screw 13 may serve the function of locking the hinge part in adjusted position. The pintle 4 in FIGS. 2 and 3 is preferably separate from 45 the cylindrical member 1.

In FIG. 4 the hinge is shown as mounted on a rabbeted door, the hinge part 1 being fastened to the stationary frame 10 by means of the pin 3, while the hinge part 2 is supported by means of the pin 5 into the movable door 11 provided with a rabbet 11a. The upper part 2 is fitted on the pintle of the lower part and moves with the door. The locking member 7 is arranged above the pin 3 and engages a recess provided in the hinge part 1. The hinge pin 5 may be driven into the rabbet angularly as 55 shown. The hinge of the invention is also suitable for non-rabbeted doors engaging the frame with a butt joint or offset joint.

The design of the locking members as a separate part 60 and the fact that the bolt which, in accordance with FIG. 1, is used as the locking member is provided, at its end engaging the bore 8 of the lower part 1, with a screw slot are of particular advantage for the conventional method of mounting doors. In conventional practice, doors of, for example, a cabinet are first fastened on approval prior to polishing the cabinet and are then removed whereupon they are finally mounted. The lower part 1 and the upper part 2 are fastened to the frame and the door, respectively, of the cabinet by means of a suitable fastening tool.

65 Driving in of, for example, a stud bolt of an eye screw as a locking member is possible with the same fastening tool without resetting the same. In the preliminary fasten-

ing and mounting of the cabinet, the stud bolt is driven in to an extent that its upper end is flush with the wood surface, i.e., it will not engage the lower hinge part 1 so that the same is not yet secured against rotation out of position and, just as the upper part 2, may be removed by unscrewing. Thereafter, the polish is applied to the cabinet. After the polishing is completed, the stud bolt is unscrewed from the wood by the depth of the bore 8, e.g. by 2 mm., by means of a screw driver engaging the slot of the stud bolt. The upper part 2 and the lower part 1 are now finally screwed in, i.e., the upper part is screwed in completely and the lower part to an extent that the stud bolt 7 arrives at the beginning of the bore 8. The last part of driving in the lower hinge part 1 is effected by hammering, for the lower part 1 can no longer be turned because the stud bolt has now engaged the bore 8. To make this hammering-in possible, the pins 3 and the stud bolt are preferably provided with nail screw threads, which facilitates the hammering-in and prevents the pulling-back of the threads out of the bore. The pin 5 of the upper part, however, is preferably provided with a metric thread which permits a finer regulation of the depth of penetration of the pin into the wood when adjusting the distance between the frame and the door. The eye screw 13, which is provided preferably with a thread used on spikes, will be installed on doors having veneer loosely between the upper part and the lower part of the hinge, so that the eye screw will lie in the opposite direction to the door. The screw will be fastened in the bore when fastening the hinge finally.

The bore 8 for the locking member may be of elongated shape in the direction of the axis of the hinge part.

Securing of the pins 3 and 5 and also of the pintle 4 in the respective hinge part 1 or 2 is preferably effected by manufacturing the hinge parts 1 and 2 as castings (of die-cast metals or of injection-molded plastics) and by imbedding the pins 3 and 5 and the joint rod 4 directly into the casting. To improve the tight fit between the imbedded parts and the casting, the members 3, 4, and 5 may be roughened, e.g. knurled, at their ends or be provided with thicker heads 3a, 3b, 3c (FIGS. 6 through 8). Instead of imbedding the two parts 3 and 4 into the lower hinge part 1, both of the members 3 and 4 may be used as an integral piece of angular shape 4a (FIG. 5). The angular shape alone prevents the imbedded member from being turned out of position with respect to the casting 1 and from being pulled out.

The imbedding of the pins 3 and 5 in the hinge parts 1 and 2 permits hinges of different sizes to be provided with pins 3 and 5 maintained at the same spacing. While previously the distance between the pins and the thicknesses thereof were increased as the size of hinge increased, this is not required in the hinge of the invention. It is only necessary for optical reasons to increase the lengths of the hinge members 1a, 2a, 1b, 2b, 1c, and 2c (FIG. 9); note the spacing of pins 3 and 5 is the same for all the hinge members.

In case of the embodiment of the hinge of the invention shown in FIGS. 10 and 11, the upper hinge part 14 is provided with a cross pin 15 while the lower hinge part 16 is provided with a transversely extending pin 17. Both of the cylindrical hinge parts 14 and 16 are pivotally mounted about a common rod 18. The pins 15 and 17

are provided at their inner sides with elongated threaded recesses 19 and 20 into which the bolts 21 may be screwed as locking members while displacing the wood not removed by preliminary drilling. Thereby, the pins 15 and 17 are locked in the wood under additional pressing power in a simple and reliable manner preventing them from being turned and pulled out and permitting easy replacement.

The elongated threaded recesses in the pin and the screws 21 are of equal length. Therefore, the headless screws 21 mating with the elongated threaded recesses of the metallic pins can not be screwed in too deep. Its front end will be flush with the front face of the pin and the surfaces of the door and the frame even in case of inadvertent driving. In case of the hinge for doors provided with rabbets as shown in FIG. 10, the pin 15 is provided with a flattened part 22. The elongated threaded recess 19 begins at the non-flattened part of the pin 15.

What is claimed is:

1. A hinge assembly for use between a pair of panels or the like having respective relative movement, said assembly comprising two elongated barrel portions, one of said barrel portions including at one end a longitudinally extending pintle element, the other barrel portion including at one end a longitudinally extending bore opening thereinto and rotatably and removably received on said pintle element, each of said barrel portions including a laterally projecting, drivable fastener disposed normal to the longitudinal axis of said barrel portions and disposed at an intermediate portion of said barrel portions for respective receipt in one of said pair of panels to be hingedly connected by said hinge assembly, and drivable fastener means mounted on said pintle element and disposed between said one ends thereof, said drivable fastener means including an elongated end portion disposed normal to the longitudinal axes of said barrel portions.

2. A hinge assembly as set forth in claim 1 wherein said drivable fastener means comprises a bifurcated staple element having an eye portion circumscribed about said pintle and disposed within a projection of the outer surface of said barrel portions.

3. A hinge assembly as set forth in claim 1 wherein said drivable fastener means comprises a screw-eye having an eye portion circumscribed about said pintle and disposed within a projection of the outer surfaces of said barrel portions.

4. A hinge assembly as set forth in claim 1 wherein the drivable fasteners on said barrel portions are spaced longitudinally equidistantly from said one ends of said barrel portions.

5. A hinge as in claim 1, wherein each barrel portion is die-cast metal.

6. A hinge as in claim 1, wherein each barrel portion is injection-molded plastic material.
